RAZOR BLADE DRIER AND CONTAINER

Samuel S. Vineberg, Buffalo, N. Y.

Application September 23, 1942, Serial No. 459,400

7 Claims. (Cl. 206—46)

This invention relates to a combined drier and holder or container for use with safety razor blades of the thin, flat and usually double-edged type in extensive use at the present time, for drying the blades after shaving and for enclosing and protecting one or more blades to keep them in good condition ready for use.

One object of my invention is to provide a combined drier and container for razor blades which is of practical and desirable novel construction; which can be readily used for drying a blade after its use for shaving, and for conveniently storing and protecting it alone or together with other blades until needed for use; which is of simple and inexpensive construction; which is of neat and attractive appearance and of small compact size adapting it to be placed in the usual small razor set receptacle or box for preserving and protecting one or more razor blades until needed for use.

Further objects and advantages of the invention will appear from the following specification of the preferred embodiments of the invention shown in the accompanying drawing, and the novel features of the invention are set forth in the appended claims.

In said drawing:

Fig. 1 is a perspective view of a razor blade drier and container of one form embodying my invention and showing the same open ready to receive a blade for drying it after use thereof, and showing blades therein.

Fig. 2 is a plan view of the device in one open position thereof.

Fig. 3 is a plan view thereof in closed condition, with the closing flap partly broken away.

Fig. 4 is a fragmentary plan view showing the manner of securing the filler strip in the cover.

Fig. 5 is a plan view, broken away, of a slightly modified form and illustrating one way of removably securing the filler strip in place.

Fig. 6 is a fragmentary plan view of the cover of the form shown in Fig. 5 before attachment of the filler.

Fig. 7 is a fragmentary plan view showing still another manner of securing the filler and cover together.

Fig. 8 is a fragmentary, longitudinal section thereof on line 8—8, Fig. 7.

Referring first to the embodiment of the invention shown in Figs. 1—4 of the drawing, the device comprises a cover 10 and an inner body or filler 11 in the form of a strip of absorbent sheet material, such for example as blotting paper, which is pleated or folded upon itself to

form a plurality of folded or double ply leaves between which a razor blade or blades can be placed and dried by closing the leaves against opposite sides of the blade or blades, said cover being provided with fastening means for holding it closed about the folded absorbent filler for retaining the blades in position between the filler leaves and protecting them. The cover may be made from suitable sheet material, such for instance as card stock, imitation leather or other relatively thin, stiff and preferably non-absorbent material, which cover may consist of a strip of such material creased or scored along the lines 12 and 13 to form opposite cover leaves 14 and 15, connected by an intermediate back or hinge portion 16 to adapt the leaves to hinge or close and open towards and from each other like the covers of a book. For the purpose of releasably fastening the two cover leaves in closed position to hold the filler leaves closed against the razor blade or blades between them, one cover leaf 15, as shown, is provided at its free end with an extension or flap 17 creased or scored along the lines 18 to adapt it to be folded over the free ends of the folded filler leaves, and having a tongue 19 at its end adapted to be inserted and held in a slit 20 in the other cover leaf 14 adjacent its free end for fastening the cover leaves in their closed position.

The pleated filler strip is suitably secured at one end to one end of the cover to retain it in place therein, but the opposite end of the filler strip, as shown in this form of the device, is left unattached to the cover. For instance, the filler strip may be secured to the cover as by a wire staple 21, or stitching, see Figs. 1 and 4, passing through the cover leaf, the filler strip and an inwardly folded flap or tab on the adjacent end of the cover. The cover is also provided at the opposite sides of the cover leaf 14 with laterally projecting, foldable flaps 22 adapted to be folded inwardly between the closed filler leaves and the cover leaf 15. As shown in this construction, these side flaps 22 are formed by the projecting ends of a separate flap strip 23 which is arranged transversely in the cover and secured between the filler strip and the cover by the same staple or stitching 21 that fastens together the filler and cover strips. These side flaps could be integral side wings or portions of the cover strip, but the use of the separate flap strips 23 prevents the waste that would result from cutting or blanking out cover strips with integral flaps. When the cover is closed with the side flaps 22 folded in between the cover and the absorbent

filler, the razor blades are securely retained in place between the absorbent filler leaves and prevented from accidental escape from the closed container, since the cover thus closes or covers both the opposite sides and opposite ends of the filler leaves.

It will be noted that the pleats or folding lines of the filler strip extend from side to side thereof, that is, parallel with the free edges or folding lines of the cover, and the dimensions of the filler leaves are only sufficiently larger than those of the razor blades to fully cover the blades when the leaves are closed, while the cover is only of sufficiently larger dimensions than the folded filler to enable the cover when closed to properly enclose the filler. Thus, the device is small and compact enough to adapt it to be used in the small razor set cases or receptacles now in extensive use in place of the blade container that is ordinarily supplied with the razor set.

Preferably, the cover strip is embossed to provide a marginal bead 24 along its opposite side edges and at its free end. This embossed bead forms a raised or offset flange which stiffens the edge portions of the cover strip and acts to hold the cover leaves flat or prevent them from bowing or bending between the folding lines of the cover strip. This preserves the flat, neat exterior appearance of the leaves of the cover and stiffens them so as to better hold the filler leaves firmly closed against the intervening blades. Preferably the bead is continued around the free end and securing tongue 19 of the cover to stiffen it, and a similar bead 25 is also embossed on the cover leaf 14 along the tongue slit 20. This slit, as shown, has an oblique extension 26 at one end to better facilitate the insertion and removal of the tongue into and from the slit, and the bead 25 is shown as continued across the opposite straight end of the slit, to thereby lessen the possibility of the slit being torn or enlarged in the use of the device. The embossed bead at the side edges of the cover strip is broken at the folding lines of the cover, or that is, the folding creases extend through the bead, so that the bead will not prevent the intended folding of the cover at the folding lines.

The razor blade drier and container constructed as described is especially desirable and practical for the intended purpose and has various advantages. When the device is opened and laid open-side up, on a table or stand, it will present an open condition such as indicated in Fig. 1, in which the absorbent filler leaves are more or less spread apart or separated so that a desired blade therein can be easily removed for use, and when the user has finished shaving, the blade, after being rinsed, and while still wet, can be readily dropped from the razor into a space between two of the absorbent leaves without the user having to touch the blade to remove it from the razor or place it in the drier. This eliminates liability of cutting the fingers, which frequently occurs in removing such blades from the razors and wiping them. It is then only necessary to close the absorbent leaves into contact with the opposite faces of the blade to dry it, and the device can be left open on the table until the blade is to be used again, or it can be closed and the cover fastened if it is desired to put the device away or pack it for travelling. When the container is so closed, with the cover fastened, the blades will be securely retained in place and prevented from accidental escape from

the container and will be protected from injury and rusting when not in use. When the device is left with the leaves spread open, as in Fig. 1, the moisture will readily evaporate therefrom and dry out the absorbent material. It will be noted that when the leaves of the filler are closed, the leaf next to the attached end of the filler strip will overlie and cover the securing staple 21 for the strip, and thus prevent possibility of the cutting edge of the blade from contacting and being injured by the securing means. There is no part which can engage and dull or injure the cutting edge. Nevertheless, this disposition of the securing means enables the device to be made of smaller dimensions, since in its closed condition, the securing means will be located between the folded edges of the filler leaves, so that no additional width of the leaves is necessary for securing the filler in the cover, and the leaves may be, as stated, approximately of the same or only very slightly larger dimensions than the razor blades. Thus, the device is of small size and of exceedingly simple and inexpensive construction, making it suitable, for instance, to be distributed free to users, as an advertising or sales promotion medium. The described design and construction of the device saves material and die-cutting costs because of the separate piece used for the side flaps, instead of cutting a cover strip having the flaps from a solid piece, thus eliminating waste. Because of the small size and simple construction, the device can be produced cheaper than previous driers. Assembling and processing costs have been cut to the minimum. The described embossing strengthens and stiffens the cover and better preserves its flat, rectangular and neat appearance, and ensures a tighter closure and better drying and protection of the blades, and prevents the tearing of the fastening tongue or slit.

In the device illustrated, the free end of the filler strip is provided with a slit 27 in which the cover fastening tongue 19 can be inserted if desired, when the filler is spread out, as shown in Fig. 1, to thus insure holding the absorbent leaves open or separated. This slit may be used or not, as preferred.

The modified form of the device shown in Figs. 5 and 6 may be substantially the same as above described and shown in Figs. 1-4, except that in this form of the device the cover piece or strip 10a has integral projecting wings or portions forming the foldable side flaps 22a instead of the flaps being formed by a separate flap strip, as first described, and the absorbent filler strip is removably secured in the cover by integral parts of the cover engaging the filler strip. For instance, as shown, the cover is provided at one end with an inwardly folded extension 30 having a slot 31 therein extending cross-wise of the strip, into which an adjacent end of the filler strip 11a is inserted, and the filler strip is provided with holes 32 through which tongues 33 on the extension 30 at the inner side of the slot 31 are inserted and bent over to secure the filler strip in place. Otherwise this embodiment of the invention may be of the same construction as shown in Figs. 1-4.

Figs. 7 and 8 illustrate another slightly modified way of securing the filler strip in the cover. As here shown the cover, like that in the first construction, comprises a main straight cover strip 10b and a separate, transverse flap strip 23b which forms the foldable side flaps 22b of

the cover, and the cover strip 11b is provided with the inwardly folded securing extension 30 of the form shown in Figs. 5 and 6, but in this construction the tongues 33 of the securing extension are inserted through registering holes in the filler strip and in the flap strip 23b, thereby securing both the filler strip and flap strip in place in the cover.

In the embodiments shown in Figs. 5-8, the absorbent filler strip is removably secured in the cover, thus enabling replacement of an old or used filler strip or refills to be used in the same cover. This makes the cover of more permanent value and saves the user expense. A cover or leather or more expensive or desirable material could therefore be used with economy.

As clearly shown in Fig. 2 of the drawing, the cover fastening tongue 19 is undercut or of hook form at one side while the opposite side edge of the tongue slopes back at an obtuse angle to the adjoining edge of the flap 17. Due to such form, the tongue can be easily engaged in the slit 20 by first inserting the point of the hook in the slit in an oblique direction and the tongue can be easily disengaged by an opposite oblique pull on the flap 17. Nevertheless the hooked end of the tongue will engage the adjacent end of the slit and prevent its accidental withdrawal from the slit and opening of the cover by a direct lengthwise pull on the tongue flap. The embossed bead along the inner side of the slit further facilitates the insertion of the tongue, since it tends to hold this edge of the slit from bending while pressure on the tongue will depress the opposite edge of the slit more easily and thus open it. By making the slit in the edge or side of the bead also aids in the insertion of the tongue because the inner edge of the slit is thus on the sloping side of the bead or somewhat above the opposite edge of the slit.

I claim:

1. A razor blade drier and container comprising a cover of relatively thin stiff sheet material having two leaves hingedly connected to close and open towards and from each other like the covers of a book, and a filler consisting of a separate long narrow strip of absorbent sheet material pleated to form folded leaves and disposed between the cover leaves with its pleat folds parallel with the free end edges of the cover leaves, said filler strip being secured at one end thereof to the inside of one of said cover leaves, said cover having at its opposite sides foldable flaps adapted to be folded inwardly between the cover and said filler when the filler leaves are closed together, and means integral with said cover for releasably fastening the leaves in closed position to retain one or more blades in place between said absorbent leaves.

2. A razor blade drier and container comprising a cover of relatively thin stiff sheet material having two leaves hingedly connected to close and open towards and from each other like the covers of a book, and a filler consisting of a separate long narrow strip of absorbent sheet material pleated to form folded leaves and disposed between the cover leaves with its pleat folds parallel with the free end edges of the cover leaves, said filler strip being secured at one end thereof to the inside of one of said cover leaves, and a separate elongated flap strip secured crosswise in said cover and forming projecting foldable flaps at opposite sides of the cover adapted to be folded inwardly between the cover and said filler when the filler leaves are closed together,

and means integral with the cover for releasably fastening the leaves in closed position to retain one or more blades in place between said absorbent leaves.

5. 3. A razor blade drier and container comprising a cover strip of relatively thin stiff sheet material folded to form two connected leaves arranged to close and open like the covers of a book, and a filler consisting of a separate strip of 10 absorbent sheet material pleated to form folded leaves and disposed between the cover leaves with its pleat folds parallel with the free end edges of the cover leaves, one leaf of said cover strip having at its free end an extension folded in between the cover leaf and the filler and attached to the adjacent end of said filler strip for securing the filler in the cover, and means integral with the cover for releasably fastening the leaves in closed position to retain one or more blades in place between said absorbent leaves.

25 4. A razor blade drier and container comprising a cover strip of relatively thin stiff sheet material folded to form two connected leaves arranged to close and open like the covers of a book, and a filler consisting of a separate strip of absorbent sheet material pleated to form folded leaves and disposed between the cover leaves with its pleat folds parallel with the free end edges of the cover leaves, said cover strip having an integral extension thereof at one end folded inwardly and having integral portions which interlock with integral portions of the adjacent end of said filler strip for securing the 30 filler in the cover, and means integral with the cover for releasably fastening the leaves in closed position to retain one or more blades in place between said absorbent leaves.

35 5. A razor blade drier and container comprising a cover of relatively thin stiff sheet material having two leaves hingedly connected to close and open towards and from each other like the covers of a book, and a filler consisting of a separate strip of absorbent sheet material pleated to form folded leaves and disposed between the cover leaves with its pleat folds parallel with the free end edges of the cover leaves, said filler strip being secured at one end thereof to the free end of one of said cover leaves, said other cover leaf having a foldable fastening extension 40 with a tongue arranged to engage in a slit in the first cover leaf for releasably fastening the leaves in closed position to retain one or more blades in place between said absorbent leaves, and said tongue also being adapted to be inserted in a slit in the free end of said filler strip to retain the filler leaves in opened position.

45 6. A razor blade drier and container comprising a cover strip of relatively thin stiff sheet material folded to form two connected leaves arranged to close and open like the covers of a book, and a filler consisting of a separate strip of absorbent sheet material pleated to form folded leaves and disposed between the cover leaves with its pleat folds parallel with the free end edges of the cover leaves, an elongated flap strip 50 arranged crosswise between the filler and one cover leaf and forming projecting foldable side flaps adapted to be folded inwardly between the second cover leaf and the filler when the filler leaves are closed together, and a single means fastening the filler and flap strips to said first cover leaf for securing said strips in the cover, and means integral with the cover for releasably 55 fastening the leaves in closed position to retain

one or more blades in place between said absorbent leaves.

7. A razor blade drier and container comprising a cover strip of relatively thin stiff sheet material folded to form two connected leaves arranged to close and open like the covers of a book, and a filler consisting of a separate strip of absorbent sheet material pleated to form folded leaves and disposed between the cover leaves with its pleat folds parallel with the free end edges of the cover leaves, an elongated flap strip arranged crosswise between the filler and one cover leaf and forming projecting fold-

able side flaps adapted to be folded inwardly between the second cover leaf and the filler when the filler leaves are closed together, said first leaf of the cover having at its free end an extension folded in between the cover leaf and the filler and attached to the adjacent end of the filler strip and to the flap strip for securing said strips in the cover, and means integral with the cover for releasably fastening the leaves in closed position to retain one or more blades in place between said absorbent leaves.

SAMUEL S. VINEBERG.
